UNITED STATES PATENT OFFICE.

LOUIS A. SHERMAN, OF PEMBROKE, MASSACHUSETTS.

MARINER'S LIQUID COMPASS.

1,024,810.

Specification of Letters Patent. Patented Apr. 30, 1912.

Application filed January 12, 1911. Serial No. 602,536.

To all whom it may concern:

Be it known that I, LOUIS A. SHERMAN, a citizen of the United States, and a resident of Pembroke, in the county of Plymouth and State of Massachusetts, have invented certain new and useful Improvements in Mariners' Liquid Compasses, of which the following is a specification.

My invention relates to improvements in mariners' liquid compasses, and the objects of my improvements are, first, to provide means for the artificial illumination of the compass card either wholly or in part; second, the introduction of a source of illumination to reflect on the compass card points immediately under the eyes of the helmsman; third, the provision of a reflector throwing light upon that portion of said card to be read and further acts as a shield to the sight; fourth, a detachable bottom to the compass bowl, and in other essentials hereinafter specified and particularly defined in the claims.

In the drawing forming a part of this specification, Figure 1, denotes a transverse section of the organized compass, Fig. 2, is a plan of the bowl exhibiting the shield with its reentering angle visually exposing the card points immediately under reading. Fig. 3, designates an alternate form of the attachment admitting light to the interior of the compass bowl.

Corresponding letters of reference designate similar features throughout the several figures of the drawing, referring to which:—

A represents the compass bowl and B the gimbal ring suspending the same in the usual manner.

C designates the detachable cup properly weighted to maintain equipoise, and secured to the bottom of the bowl by bayonet slots and pins as at D thus permitting removal for examination and repair if needed to the illuminating fixtures. These, comprise the base E surmounted by the bulb F forming the inclosure for the electric light, said bulb may consist of white, green or red glass or frosted bulbs as desired, posts G are anchorages for the wires transmitting the electricity from batteries or other sources of electric energy. Immediately above the bulb F will be observed the light admitting attachment H composed of non-magnetic metals supporting the glass I protected by a ring of composite material J

preferably composed of tin and lead in certain proportions, or other suitable material may be used, the aggregation, by fusing becoming a part of said attachment and is 60 supported by the diaphragm K to which it is attached and above which is the disk L supporting the compass card M and permitting the penetration of the light rays through the aperture N in the compass card 65 to the slidable reflector O, which, to insure greater efficiency in light concentration may be concaved, the perimeter being broken as at P (Fig. 2) to provide the reentering angle Q, or any other desirable form of 70 aperture which will permit the light to reach the segment of that portion of the compass card it is desired to illuminate for the purpose of a clearer and quicker interpretation of the characters thereon, said 75 reflector being adapted to be moved about its axis or to be raised from its seat, when readjusting to expose a different segment of the card.

In the construction of my improved compass, the source of artificial illumination may be at other portions of the bowl other than as illustrated; the distinctive feature being the equalized diffusion of light about the compass card and its concentration upon 85 the points of rhumbs to be read without interference to the vision by exposed rays of light as exemplified in the ordinary binnacle.

The arrangement of the illuminating features are such also as to preclude any disarrangement thereof through the erratic oscillation of the compass bowl, and the light may, further, be increased by the employment of suitable lens as at I' Fig. 3 if 95 thought desirable, and while there may be other modifications structurally departing from the precise manner illustrated, I desire not to be held to the strict interpretation herein disclosed but may use such 100 equivalents therefor as would come within the fair scope and spirit of my invention, which, having thus described, I desire to secure by Letters Patent of the United States, and I claim:—

1. The herein described mariner's compass comprising a bowl having a source of light interiorly, a lens projecting the rays of light from said bowl, an illuminated inclosure confining the compass card and a 110 surmounted movable reflector adapted to deflect said light rays upon the rhumbs de-

picted on the reading surface of the compass card.

2. The combination with a compass having a detachable weighted cup provided with means for the illumination of the compass interior of a removable slidable reflector having a broken perimeter to render visible any desired segment of the compass card, a centrally apertured disk supporting said card, a sustaining diaphragm, a lens thereby supported for the projection and diffusion of light throughout the interior of the compass.

3. In a mariner's compass a bowl containing means for the artificial illumination of the bowl interior, a diaphragm bearing a light admitting attachment, a disk adapted to support the compass card and having a central opening for the penetration of the light, a compass card having a light penetrating aperture and means for the reflection of light downward upon the face of said card.

4. A compass bowl adapted for interior illumination and having a source of light producing energy, means permitting the

penetration of the rays of light upward, a disk adapted to support the compass card, and a slidable reflector having a reentering aperture extending from its perimeter through which certain of the rhumbs of the compass card are read by reflected light.

5. The herein described mariner's compass comprising the following instrumentalities, to wit:—a bowl having a detachable weighted cup, a base mounted on said weight and provided with means for the illumination of said bowl interior, a diaphragm and means centrally located therein for admission of artificial light upward, a disk supporting the compass card and permitting the expansion of said diaphragm, a reflector reflecting the light against the reading surface of the compass card, said reflector having an opening to expose any segment of the compass card.

In testimony whereof I have affixed my signature, in presence of two witnesses.

LOUIS A. SHERMAN.
